(57) **CLAIM**

The ornamental design for a socket wrench tooth, as shown.

DESCRIPTION

FIG. 1 is a perspective view of a socket wrench showing my new design;

FIG. 2 is a front view thereof;

FIG. 3 is a top view thereof;

FIG. 4 is a A-A cross-section view thereof;

FIG. 5 is a B-B cross-section view thereof;

FIG. 6 is a perspective view of a socket wrench showing my new design; and,

FIG. 7 is a perspective view of another socket wrench showing my new design.

The broken lines depict portions of the socket wrench tooth that form no part of the claimed design.
